UNITED STATES PATENT OFFICE

NICOLA DI BARTOLOMES, OF BROCKTON, MASSACHUSETTS

ELEVATOR APPARATUS

Application filed July 18, 1930. Serial No. 468,811.

My invention relates to elevator apparatus and it has for its object to provide an apparatus of this class of simple, efficient and inexpensive construction particularly adapted for use in connection with the shaft of a mine or the like and so constructed that an operator located upon the surface of the ground may control the movements of the car.

10 To these ends I have provided an elevator apparatus having the peculiar features of construction and mode of operation set forth in the following description, the several novel features of my invention being particularly pointed out and defined in the claims at the close thereof.

In the accompanying drawings:

Figure 1 is an elevation, viewed from one side, of an elevator apparatus constructed in accordance with my invention.

Figure 2 is an elevation of the apparatus shown in Figure 1 as viewed from the left in the latter figure.

Figure 3 is a section on line 3—3 of Figure 1.

Having reference to the drawings A is the shaft of a mine or the like within which is provided a framework 1 constructed in most part from timbers and being approximately rectangular in cross section as shown in Fig. 3.

This framework 1 supports a pair of vertical metal rails 2, 2 which are rigidly fastened upon the inside of the frame 1 and upon opposite sides thereof. Mounted to slide vertically upon these rails 2, 2 is a car 3 to the top of which are fastened the lower ends of four cables 4, one near each corner of the car. The upper ends of these cables 4 are fastened to a coupling member 5, which in turn is fastened to one end of a wire cable 6 which extends upwardly therefrom over a sheave 7 rotatably supported at the top of the frame 1, and thence downwardly to a drum 8 to which its opposite end is fastened. This cable 6 is sufficiently long to permit the car 3 to move vertically from its uppermost position illustrated in the drawings to the bottom of the shaft A.

50 The drum 8 is fixed upon a shaft 9 on which

is secured a beveled gear 10 meshing with a beveled gear 11 that is compounded with a spur gear 12 rotatably supported by a stud shaft 13 secured to an upright 14.

The upright 14 is rigidly secured to a platform 15 that is supported in an elevated position above the ground by posts 16 whose lower ends are secured to a base 17.

The spur gear 12 meshes with another spur gear 18 located directly above it and fast on a shaft 19 that is journaled in bearings provided upon the upright 14 and another upright 14a.

The shaft 9 is journaled in bearings provided upon uprights 20.

The shaft 19 has loosely mounted upon it two comparatively wide pulleys 21 and 21a between which is disposed a relatively narrow pulley 22 that is fastened rigidly to the shaft 19.

The pulleys 21, 21a and 22 have associated with them two belts 23 and 24, the former being straight and the latter crossed and these two belts extend around a drum or pulley 25 that is rotatably supported by a shaft 26 journaled in uprights 27 provided upon the platform 15.

Mounted upon the base 17 beneath the platform 15 is an electric motor M whose armature shaft 26a, Fig. 2, carries a pulley 27 connected by a straight belt 28a with the pulley or drum 25.

When the motor M is in operation, the drum 25 is continuously rotated in one direction and it will be clear that when the belt 24 is on the fast pulley 22, the shaft 19 and gear 18 are driven in one direction and when the straight belt 23 is on the fast pulley 22, the shaft 19 and gear 18 are driven in the opposite direction. It will also be clear that when the belts 23 and 24 are on the loose pulleys 21 and 21a, shaft 19 and gear 18 are at rest. Thus by controlling the positions of the two belts 23 and 24, the car 3 may be raised, or lowered, or held stationary.

The two belts 23 and 24 are both engaged by a shipper member 28 having a rigid stem 29 slidable endwise in bearings on uprights 30 provided upon the top side of the platform 15. At one end thereof the stem 29 is

pivotedly connected at 31 with one end of a connecting rod 32 whose opposite end is pivotedly mounted upon a wrist pin 33 projecting from one face of a wheel 34 fast on a shaft 35 journaled in bearings on uprights 36 provided upon the top side of the platform 15. This shaft 35 also carries a grooved pulley wheel 37 from the outer face of which projects a crank handle 38 by means of which the shaft 35 is manually rotated. It will be clear that rotation of shaft 35 and wheel 34 acts through the connecting rod 32 to shift the shipper 28 longitudinally with respect to shaft 19 so that the mechanism just described provides means through which the shipper member 28 is manually adjusted to cause the pair of belts 23 and 24 to occupy either of the three positions referred to above.

20 The wheel 34 is formed upon its periphery with three notches *a*, *b* and *c* to co-operate with a roll 39 rotatably supported by a detent arm 40 that is pivotedly mounted at 41 upon the frame 1 so as to have capacity for 25 swinging movement toward and from the wheel 34. The detent arm 40 is firmly but yieldingly urged toward and against the wheel 34 by means of a spring 42.

The roll 39 of the pivotal detent arm 40 is adapted to seat within either of the notches *a*, *b* or *c* and while occupying position therein to yieldingly hold the wheel 34 against accidental rotative displacement.

30 The notch *a* is positioned upon the periphery of the wheel 34 so that when belt 24 is on loose pulley 21a and belt 23 is on the tight pulley 22, the roll 39 occupies position therein and yieldingly holds the shipper 28 in that position. Also the notch *b* is located 35 on the periphery of wheel 34 so that when roll 39 occupies position therein the shipper 28 maintains the belt 23 on loose pulley 21 and the belt 24 on loose pulley 21a. When the roll 39 occupies the notch *c* of wheel 34, as 40 shown in the drawings the shipper 28 occupies a position where it holds the crossed belt 24 on the tight pulley 22 and the straight belt 23 on the loose pulley 21. Thus the engagement of the pivotal detent arm 40 with 45 either notch *a*, *b* or *c*, not only serves to yieldingly hold the shipper 28 in its selected operative position but to also accurately position the pair of belts 23 and 24 with respect to the pulleys 21, 22 and 21a.

50 Fast upon the outer end of the stem 29 is a sleeve 43 provided upon its opposite sides with pairs of ears to which are pivotedly connected the inner ends of a pair of toggle links 44 whose outer ends are formed with 55 slots 45 occupied by studs 46 provided at the free ends of a pair of brake shoes 47. These brake shoes 47 are pivotedly supported at 48 upon a stud projecting from the upright 14a by which stud said brake shoes are supported within a brake drum 49 fast on the

shaft 19. A spring 50 having its opposite ends connected with the two brake shoes 47 serves to yieldingly hold said shoes at the limit of their movement toward each other normally.

When the shipper 28 is at the limit of its movement toward the left, Fig. 2, the inner ends of the toggle links 44 are at one side and to the left of a vertical plane extending through the studs 46, but when the shipper 28 is moved toward the right, Fig. 2, into its intermediate position the pivots 51 at the inner ends of the toggle links 44 occupy positions within the same vertical plane with the studs 46 and the inner ends of the slots 45 then force and hold the brake shoes 47 against the interior of the brake drum 49 thereby locking the shaft 19 against rotation in either direction while shipper 28 occupies its intermediate position. It will be clear that when the shipper 28 occupies this intermediate position the pair of belts 23 and 24 are on the loose pulleys 21 and 21a. When the shipper member 28 is shifted from its intermediate position to the limit of its movement toward the right, Fig. 2, the pivots 51 at the inner ends of the toggle links 44 are carried into positions at the right of a vertical plane extending through the studs 46 thereby permitting the spring 50 to unset the brake shoes 47 and free the shaft 19. It will also be clear that when the shipper 28 is at the limit of its movement in the opposite direction and the crossed belt 24 is driving shaft 19, the pivotal connections 51 are disposed as shown in Fig. 2 and the brake shoes 47 are held out of engagement with the brake drum 49 by the spring 50. Thus the shipper member 28, including its stem 29, automatically operates and controls the brake shoes 47 so that the brake is unset when either belt 23 or belt 24 is on the tight pulley 22 and said brake is set and shaft 19 is held at rest when the pair of belts 23 and 24 are on the loose pulleys 21 and 21a, respectively.

Beneath the elevated platform 15 is provided a grooved pulley 52 which is connected with the grooved pulley 37 by means of a belt 53, said pulley 52 being rotatably supported by a shaft 54 supported by the frame of the apparatus and, like the pulley 37, being provided upon its outer face with a crank handle 55, accessible to a person standing upon the base 17. Thus the shaft 35 may be operated either by a person on the platform 15 or by a person standing on the base 17.

I have herein shown the car 3 as provided upon its top with safety mechanism by means of which it is supported in the event that the cable 6 is broken. This mechanism includes a pair of brake shoes 56 slidably connected with the top wall of car 3 each of which is made with a pair of inwardly extending stems 57 and each stem 57 is con-

nected with one of the four cables 4 so that the tension on the cables 4 due to the weight of the car 3 serves to hold the brake shoes 56 retracted against the pressure of springs 58 surrounding the stems 57. In the event that the cable 6 is broken the resulting slackness of the cables 4 permits the springs 58 to force the brake shoes 56 outwardly against the rails 2 thereby preventing or retarding the fall of the car 3.

What I claim is:

1. In an elevator apparatus, in combination, a cable-operating shaft; two pulleys loosely mounted on said shaft; a third pulley tightly mounted on said shaft between said two loose pulleys; a pair of driving belts co-operating with said pulleys one of which is crossed and the other straight; brake mechanism for said shaft including a pair of movable brake shoe members; a manually controlled shipper member for shifting both belts sidewise simultaneously, means slidably supporting said shipper member alongside of said pulleys so that it is movable endwise on a rectilinear path parallel with said shaft; a shipper operating member that is manually adjusted rotatively; a connection through which said member when rotated acts to shift said shipper member endwise; detent means for engaging and yieldingly holding said shipper operating member in either of three different predetermined positions, and two links disposed upon opposite sides of said shipper member, each having one end thereof pivotally connected with said shipper member directly opposite the pivoted end of the other link so that forces imposed endwise on said links are opposed, and having its opposite end portion connected with one of said brake shoe members.

2. In an elevator apparatus, in combination, a cable-operating shaft; two pulleys loosely mounted on said shaft; a third pulley tightly mounted on said shaft between said two loose pulleys; a pair of driving belts cooperating with said pulleys, one of which is crossed and the other straight; brake mechanism for said shaft including a pair of movable brake shoe members; a manually controlled shipper member for shifting both belts sidewise simultaneously; means slidably supporting said shipper member alongside of said pulleys so that it is movable endwise on a rectilinear path parallel with said shaft; a shipper operating member that is manually adjusted rotatively; a connection through which said member when rotated acts to shift said shipper member endwise; a detent member for engaging and yieldingly holding said shipper operating member in either of three different predetermined positions, and two links disposed upon opposite sides of said shipper member, each having one end thereof pivotally connected with said shipper member directly opposite the pivoted end of

the other link so that forces imposed endwise on said links are opened, and having its opposite end portion formed with a longitudinal slot, and each of said brake shoes having an end portion thereof occupying the slot of one of said links against which end portion the inner end wall of said slot abuts to set the brake mechanism when said shipper member occupies an intermediate position.

3. An elevator apparatus constructed in accordance with claim 2, wherein said rotatable shipper operating member is made with three recesses, each of which is occupied by said detent means at times to hold said rotatable shipper operating member in adjusted position.

CERTIFICATE OF CORRECTION.

Patent No. 1,878,823.

September 20, 1932.

NICOLA DI BARTOLOMES.

It is hereby certified that error appears in the printed specification of the above numbered patent requiring correction as follows: Page 3, line 67, claim 2, for the word "opened" read opposed; and that the said Letters Patent should be read with this correction therein that the same may conform to the record of the case in the Patent Office.

Signed and sealed this 29th day of November, A. D. 1932.

M. J. Moore,
Acting Commissioner of Patents.
